UNITED STATES PATENT OFFICE.

ROLAND EDMONDS, OF VANCOUVER, BRITISH COLUMBIA, CANADA, ASSIGNOR OF ONE-THIRD TO LAWRENCE BRAIM AND ONE-THIRD TO VERNON CHARLES CROFTS, BOTH OF VANCOUVER, BRITISH COLUMBIA, CANADA.

BALL-BEARING CASTER.

1,231,510.

Specification of Letters Patent. Patented June 26, 1917.

Application filed August 23, 1916. Serial No. 116,514.

To all whom it may concern:

Be it known that I, ROLAND EDMONDS, a subject of the King of Great Britain, and a resident of the city of Vancouver, in the Province of British Columbia, Canada, have invented certain new and useful Improvements in Ball-Bearing Casters, of which the following is a specification.

This invention relates to improvements in casters, and the object of the invention is to devise a simple, practical and durable caster capable of being manufactured and sold at a low cost, in which the friction and strain are both reduced to the minimum, which is easily and quickly assembled or disassembled, and which is dust-proof, thereby providing for the maintenance of the device in a highly efficient condition at all times. A further object is to provide a 10 caster in which the caster wheel is brought almost directly under the center of the load, that is to say, under the actual center of the bearing around which the caster turns, so that an even distribution of the weight on the point of support is obtained. Application No. 131,300, filed November 14, 1916, is a division of this case.

I attain these objects by the construction illustrated in the accompanying drawings 20 in which—

Figure 1 is a side elevation of the caster. Fig. 2 is a vertical section on the line a—b of Fig. 1.

Fig. 3 is a side elevation of a modified 30 form of the caster.

Fig. 4 is a vertical section on the center line of Fig. 3.

Fig. 5 is a detail view of the collar in Figs. 3 and 4.

Fig. 6 is a plan view of the plate in Figs. 3 and 4.

Similar figures of reference indicate similar parts throughout the several views.

1 indicates a collar formed preferably as shown in Figs. 1 and 2, having a bore 2. The collar is recessed in its upper face, as shown at 3 in Fig. 2, and a plate 4 is inserted therein which plate fits the leg of the chair, table, or other piece of furniture, indicated at A in Fig. 1, to which the caster is to be attached, the plate being rigidly secured to the collar by soldering, welding, or any other suitable means. It is not however, necessary to use the plate 4 in con-

structing the assembled collar, as it may be done without, and the flat top formed by casting the collar in one piece and of the designed shape. The recess in the top and the bore may be roughly formed in the casting and drilled out to the proper diameters, 55 or the collar may be cast solid and the recess and the bore formed by drilling. The plate 4 is formed in which is provided a square opening 5, as indicated in Fig. 2. 6 indicates a sleeve adapted to fit rotatably 65 in the bore 2 of the collar and which sleeve is provided with pendent lugs 7 connected at their lower ends by means of a shaft 8, upon which shaft is journaled a caster-wheel 9. The sleeve 6 is rotatably held in 70 place when the caster is assembled by a stem 10 which fits rotatably the bore of the sleeve and which is provided on its lower end with a head 11 and at its upper end with a square portion 12 adapted to fit the 75 square opening 5 in the plate 4, from which square portion 12 extends a screw 13 by means of which the caster is secured to the furniture, a screw driver slot 14 being provided in the head 11 for driving the screw. 80 The length of the sleeve 6 is such that, when assembled, a space 15 is formed between the upper end of the sleeve and the inner face of the plate 4, in which space is carried a circular series of anti-friction 85 balls 16, which play freely around the stem 10.

The caster described in the foregoing is suitable for attachment to legs of chairs, tables and the like where a central screw 90 may be employed, but for heavy furniture where the caster is to be attached to a flat surface a slight modification in the attaching means is necessary, as illustrated in Figs. 3, 4, 5 and 6. In this construction the 95 screw 13 is done away with, the stem 10 being riveted into a plate or disk 17, as shown in Fig. 4, which is provided with countersink holes 18 through which screws are passed to secure the plate to the furniture, as shown in Fig. 3. The collar 19, which corresponds to the collar 6, hereinbefore described, is provided on its upper edge with projections 20, which fit into corresponding openings 21 in the plate 17 and 100 are riveted over to rigidly secure the collar to the plate. The rest of the construction of this modified form of the caster is the 105

same as has already been described with reference to Figs. 1 and 2.

Although I have shown, in Fig. 1, the caster attached to the furniture by means of the screw 13, I do not desire to limit myself to this method of attachment, as I may dispense with the screw and the stem 10 altogether when attaching the caster to brass or iron beds, in which case the pin found 10 on each of the feet of such beds, as will be well known to those acquainted with the art, would take the place of the stem 10 and would be passed through the plate 4 and the bore of the sleeve 6, the end of the 15 pin being then riveted over.

The operation of the caster will be apparent on reference being had to the drawing, as it will be seen that the caster wheel and sleeve turn about the stem 10 and also 20 that the balls 16 play loosely around the stem, moving in contact with the flat end of the sleeve and the inner face of the flat top 4 of the bore 2, or the plate 17 in the modification. It will be seen further that 25 as the sleeve fits rotatably the bore of the collar, dust and dirt are excluded, so that the caster is dust proof.

What I claim as my invention is:—

1. A ball bearing caster comprising a collar recessed in its upper face, said collar having a restricted neck in its upper portion, a sleeve fitting rotatably the bore of said collar, a stem on which the sleeve is rotatably mounted, said stem having its upper end 30 threaded and passing upward through the restricted neck of the collar, and anti-friction balls mounted on the upper end of the 35 said sleeve bearing upon said stem and the neck forming elements.

40 2. A ball bearing caster comprising a col-

lar, a plate co-acting therewith, a sleeve fitting rotatably the bore of said collar, a stem on which the sleeve is rotatably mounted, said stem having its upper end threaded and passing upward through the opening in the 45 collar and having a squared portion fitting the said opening, and anti-friction balls mounted on the upper end of the sleeve bearing upon said stem and said plate.

3. A ball bearing caster comprising a central stem, a uniform diameter sleeve provided with a pair of pendent lugs at its lower end rotatably mounted on said stem, anti-friction balls mounted on the upper end of said sleeve bearing upon the stem, a collar surrounding the upper end of said sleeve and adapted to inclose said balls, a plate co-acting therewith upon which said balls bear, the bore of the collar fitting the periphery 60 of the sleeve, means for securing the caster 65 in position for service, and means for preventing inadvertent rotation of said stem.

4. A ball bearing caster comprising a recessed collar, a plate inserted in said recess, a stem depending centrally from said plate, 65 a sleeve parallel throughout its length rotatable in the bore of the collar and on the stem, and anti-friction balls bearing upon the plate of the collar and the stem.

5. A ball bearing caster comprising a recessed collar, a plate inserted in said recess, a central stem extending downwardly from said plate, a uniform diameter sleeve rotatable in the bore of the collar and on the stem, and anti-friction balls bearing upon 70 the plate and the stem.

Dated at Vancouver, B. C., this 14th day of August, 1916.

ROLAND EDMONDS.
